WIRE CLIP

Application filed September 24, 1928. Serial No. 307,919.

This invention relates to clips and more particularly to wire clips which are intended to form stops on pull wires such as are used to operate valves, door bells and various other kinds of apparatus.

An object of this invention is to provide a wire clip which can be easily and quickly secured to a pull wire without the aid of special tools.

10 Another object of this invention is to provide a wire clip adapted to be clamped on a pull wire to form an efficient stop for said wire.

15 A further object of this invention is to provide a wire clip made from sheet metal which can be very cheaply manufactured and which can be secured to a pull wire without the exercise of unusual skill.

20 Another object of this invention is to provide a wire clip which can be slid along the wire so as to be quickly and easily located in proper position.

25 Other objects and advantages of this invention will appear as the description proceeds.

30 In the drawings forming a part of this application

Fig. 1 is a side elevational view of the preferred form of my clip.

Fig. 2 is an end elevational view of the clip 30 shown in Fig. 1.

Fig. 3 is a side elevational view showing an application of this form of clip.

35 Fig. 4 is a plan view partly in section of the arrangement shown in Fig. 3.

Fig. 5 shows a side elevational view of a modified form of clip.

Fig. 6 is an end elevational view of the modified form of clip shown in Fig. 5.

40 Fig. 7 is a perspective view showing an application of the modified form of clip.

The clip, as shown in Fig. 1, is formed from sheet metal and comprises a base portion indicated at 1 having a raised or ridged portion 2 extending across the mid-portion 45 of the base. The ends of the base portion are turned upwardly terminating in lugs 3. In each lug 3 there is provided a perforation 4. These perforations are so placed that the bottom edge of each perforation is on a line with the top surface of the raised por-

tion of the base. The perforations are aligned so that a straight wire may be passed through the perforations so that the wire in lying in the perforations will be tangent to the top surface of the raised portion. It 55 will be noted that these perforations are not circular in form but are elongated, having the major axis extending vertically at right angles to the plane of the base. The purpose of this elongation of the perforations will 60 appear hereinafter. The lugs which normally extend at right angles from the base portion are adapted to be bent toward each other into proximity with the ridge portion by a pair of pliers or the like and thus clamp or 65 secure the clip to a wire which is inserted through the perforations.

In Figs. 3 and 4, showing an application of the device, a pull wire 7 is shown extending through a hole 5 provided in a lever 6 which is mounted on a shaft 10. The pull wire 7 is of spring steel and is such as is commonly used for operating choke valves, automobile heater valves, door bells and the like. The clip is shown with its lugs 3 bent 75 into engagement with the wire 7 so as to form depressions or undulations 11 and 12 in the wire. The clip when thus clamped on the wire serves efficiently as a stop which may be brought against the lever 6 by pulling on the 80 wire to turn the shaft 10. A spring 8 is provided having one end secured to the lever 6 and its opposite end secured to a post 9 to return the lever to its normal position.

When the lugs are bent toward each other 85 and forced into engagement with the spring steel pull wire, the portion of the lugs between the elongated perforations and the free ends of the lugs forces the wire downwardly on each side of the raised ridged 90 portion and thus forms permanent undulations or waves in the wire. The portions of the clip interengaging with these undulations formed in the wire provide a secure connection between the clip and the wire preventing any displacement of the clip along the wire. A clip thus crimped on a pull wire 95 cannot work loose since it has no moving parts and will serve efficiently as a stop adapted to be brought against a movable 100

lever. The perforations are formed of a larger cross sectional area than the cross sectional area of the pull wire which is to be inserted through the perforations. These 5 enlarged perforations allow the clip to be quickly and easily placed on the pull wire and allow the lugs to properly adjust themselves as they are being bent. In providing the perforations of elongated form the lugs 10 may easily be bent down without binding or shearing of the wire. This elongated form of the perforation further permits the wire to be engaged only by the extreme ends of the lugs, whereby only a small portion of the 15 wire is crimped thus avoiding the necessity for excessive force in applying the clip.

Fig. 7 shows a modified form of the clip in which the clip is wide enough to accommodate two perforations in each lug. This clip 20 is shown as comprising a base portion 15 having a raised mid-portion 16 and lugs 17 formed by turning up the ends of said base portion. Elongated perforations 18 are formed in the lugs 17 so that the bottom of 25 each perforation is on a line with the top surface of the raised portion of the base. The elongations are aligned so that a wire 19 may be inserted through the clip and looped through an opening 20 provided in a valve 30 lever 21 and the free end of said loop inserted through the remaining two perforations of the clip. The lugs 17 are adapted to be bent into engagement with the wire so as to clamp both strands of wire.

35 The clips herein disclosed are intended primarily for use with pull wires which serve to operate flap valves for automobile heaters. These clips greatly facilitate the installation of such valves by providing an easy means 40 for properly adjusting the valve-operating means, since the clip can be easily slid along the wire and clinched thereon when the proper adjustment is secured, thus materially reducing the time required for installing such 45 apparatus. Likewise, such installations at service stations can more easily be made where clips of this type are used since no special tools or special skill are required in clamping the clip on the pull wire.

50 While I have described the use of this clip in connection with operating means for automobile heaters, it is to be understood that such clips can readily be used in connection with pull wires adapted for use with various kinds 55 of devices. The invention herein disclosed is not limited to the particular embodiment illustrated and described but includes such modifications thereof as fall within the scope 60 of the appended claims.

65 Having thus described my invention, I claim:

1. In combination with a pull wire, a stop 70 clamped on said wire, said stop comprising a sheet metal clip having parts adapted to be 75 bent into engagement with said wire to there-

by secure said clip to said wire by forming undulations in the wire.

2. In combination with a pull wire, a clip 70 having a base with a central ridge portion, extensions formed at the ends of said base and having aligned perforations through which said wire extends, said extensions being bent into proximity with said ridge portion to thereby form undulations in said wire.

3. A clip for a pull wire, comprising a base 75 having a ridged central portion, and a lug projecting from said base at one end thereof and having an opening through which said wire extends, said lug being adapted to be bent into proximity with said ridged portion to thereby clamp said wire between said lug and said ridged portion.

4. A clip comprising a base having upturned perforated ends, a ridge extending across said base intermediate said ends, said 80 ends being adapted to be bent into proximity with said ridge.

5. A wire clip formed from sheet metal and having a base with aligned lugs formed thereon, and a ridge formed on said base intermediate said lugs, said lugs having openings through which the wire extends and being adapted to be bent into proximity with said ridge whereby said wire is bent over said ridge and clamped between said lugs and said 85 ridge.

6. A wire clip having a base portion, aligned lugs, extending from said base portion and having aligned oblong perforations 90 therein, a ridge extending laterally across said base at its midpoint, said lugs adapted to be bent into proximity with said ridge.

In testimony whereof, I hereunto affix my signature.

LIONEL S. PECK.
